UNITED STATES PATENT OFFICE.

CARL HOFFMAN, OF ALLENTOWN, PENNSYLVANIA.

LOCK.

1,383,631.

Specification of Letters Patent.

Patented July 5, 1921.

Application filed July 16, 1920. Serial No. 396,694.

To all whom it may concern:

Be it known that I, CARL HOFFMAN, of Allentown, in the county of Lehigh and State of Pennsylvania, have invented certain new and useful Improvements in Locks; and I do hereby declare the following to be a full, clear, and exact description of the invention, such as will enable others skilled in the art to which it appertains to make and use the same.

My invention relates to locks of the type wherein latching and locking bolts are contained in a single case, and I have shown the lock of the form adapted to be mortised in a door. The object of my invention is to produce a simple and highly efficient lock of the character described with all parts compactly arranged and one wherein the latch member is operable by means of a door handle and is also adapted to be retracted by the bit of a key from outside the door, the key being used to first withdraw the locking bolt, if it has been thrown into locking position; wherein an auxiliary locking bolt is employed which is only operable from inside the door, and the movement of which into locking position causes a shield or guard to be placed over the key hole so that a key or other instrument cannot be inserted into the lock from the outside; and wherein frictionally operated stops are employed for rendering the parts inoperative.

In the drawings, Figure 1 is a view in perspective. Fig. 2 is an elevation of a portion of a door equipped with my improved mortise lock. Fig. 3 shows a lock with one of its casing plates removed. Fig. 4 is a longitudinal sectional view. Fig. 5 is a perspective view of the latch and operating lever. Fig. 6 is a perspective view of the locking bolt and one of the tumblers. Figs. 7 and 8 are details showing the latch stop and locking button, respectively.

Referring to the drawings, the mortise lock shown includes a casing 1 which is of common form having openings for the projection of the latch and locking members and for the handles to operate the latch, as well as key holes. At 2 I have indicated the latch having a beveled face with a rib for lessening the noise of contact with the keeper plate in the door frame. The latch has recesses 3 of similar formation and located on opposite sides of the latch shank so

that the latch may be reversed according to 55 the direction in which the door opens, the recesses being for the upper end of an operating lever 4 which is of L-shape and arranged for pivotal movement on the locking bolt 5. The end 6 of the lever is bent at 60 right angles to the face of the lever so as to present a widened surface to control lugs 7 and 8, respectively operated by inner and outer handles 9 and 10. The lug 7 is shorter than its complementary lug and is dependent 65 from a hub 12 supported for turning movement by a wall of the case and by the hub 13 from which depends the lug 8, the contacting surfaces of the hubs having a supporting fit each with the other, and the 70 hub 13 on its outer side being journaled in the opposite wall of the casing. These hubs have each a square opening to receive the squared end of its respective handle. Turning of either hub and the engagement between its lug and the end of the lever will 75 effect a rocking of the latter on its pivot on the locking bolt, and a retraction of the latch against its spring tension.

Movement of the locking bolt 5 is effected 80 from the outside by means of a key which must first disengage one or more tumblers 20 before the talons 21 or 22 of the bolt can be engaged by the key. The tumblers are of known form wherein a leaf spring 23 85 engaging the tumbler and a fixed stud 24 on the case tensions the tumbler to maintain it in locking engagement with the bolt so as to prevent movement of the latter. As a matter of economy I make use of one of the 90 springs 23 for maintaining the latch in extended position as well as functioning in its normal manner with the tumbler. When the bolt 5 is protracted it carries with it the operating lever 4 and in this position the 95 end 6 of the lever is beyond a point where either of the depending lugs 7 or 8 can rock the lever on its pivot. In retracting the bolt by means of a key the tumblers are first moved and the talons of the bolt are 100 then engageable by the key. When completely retracted a continued turning of the key in the same direction will cause its bit to engage the adjacent edge of the lever 4, rocking the lever and thus withdrawing the 105 latch.

Manifestly a means must be employed for use on the inside of the door which will per-

mit the locking bolt to be protracted and retracted without the use of a key and for this purpose I use the latch operating lug 7. The hub 12 carrying this lug may be turned 5 by the inside handle so as to engage talons 30, 31 at the inner end of the locking bolt, the lug 7 in this turning movement first engaging the tumblers 20 so as to release them from locking engagement with the bolt. After 10 retracting the bolt continued turning of the handle in the same direction will cause the lug to engage the end 6 of the latch controlling lever and move it to retract the latch.

15 Manipulation of the locking bolt by the outside handle is prevented by the formation of the lug 8. This lug is of greater length than its companion lug 7 and turning movement in a counterclockwise direction, which 20 would be necessary to project the lock bolt by the outside handle is prevented by contact of the lug 8 with a stop pin 35 permanently secured to the case. Movement of the lug in a direction to withdraw the lock bolt 25 is prevented by engagement of the lug with the latch operating lever and since the lever has been bodily moved outwardly with the lock bolt and is in close proximity to that wall of the casing through which the locking members project it is in a position where 30 it cannot be rocked by the lug and the latter cannot reach the lock bolt because the end 6 of the lever is in the path of turning movement of the lug. The lug 8 may be fastened 35 against any movement by a stop button 36 frictionally supported adjacent the handle 9, the shank of the button extending through the case and being adapted for projection into an aperture 37 in the lug 8.

40 In addition to the locking elements heretofore described I provide an auxiliary bolt 40 which is retained in inner or outer position by a spring held tumbler 41, the tumbler being moved by the bit 42 of a fixed key 45 just prior to engagement of the bit with the appropriate talon of the bolt. This auxiliary bolt carries a shield 43, which, when the bolt is in locking position, completely covers the key hole and prevents insertion of 50 a key or other tool from the outside.

The latch 2 may be secured against movement by a locking dog 44 frictionally held in any preferred manner in the door casing and adapted to be projected across the path 55 of the latch.

I claim as my invention:

1. A lock including a case, a spring held latch bolt, a tumbler controlled lock bolt designed for key actuation, a latchbolt operating lever carried by said locking bolt, lugs operable to engage a portion of said lever to retract said latchbolt, said lever having a second contact surface designed to be engaged by the lock bolt operating key to 60 withdraw the latchbolt when the locking 65

bolt is in retracted position, and means for preventing operation of the latch and locking bolts from one side of said case.

2. A lock including a case, a spring held latchbolt, a tumbler controlled lock bolt designed for key actuation, a latchbolt operating lever carried by said locking bolt, lugs operable to engage a portion of said lever to retract said latchbolt, one of said lugs being operable from inside the door and the other from outside the door, the inside operable lug being effective to move said lock bolt, and means for rendering said outside operable lug inoperative.

3. A lock including a case, a spring held latchbolt, a tumbler controlled lock bolt designed for key actuation, a latchbolt operating lever carried by said locking bolt, lugs operable to engage a portion of said lever to retract said latchbolt, one of said lugs being effective to move said lock bolt, said lever having a second contact surface designed to be engaged by the lock-bolt operating-key to withdraw the latchbolt when the locking bolt is in retracted position, and means for preventing movement of one of said lugs to manipulate said latchbolt from one side of said case.

4. A lock including a case, a spring held latchbolt, a tumbler controlled lock bolt designed for key actuation, a latchbolt operating lever carried by said locking bolt, lugs supported for turning movement in said case and designed to engage a portion of said lever to retract said latchbolt, one of said lugs being effective to move said lock bolt, inner and outer handles each co-operating with a lug to turn it, and means for rendering said outer handle ineffective to manipulate its complementary lug.

5. A lock including a case, a spring held latchbolt, a tumbler controlled lock bolt designed for key actuation, a latchbolt operating lever carried by said locking bolt, lugs independently operable to engage a portion of said lever to retract said latch-bolt, a hub for each lug supported in alinement by said case, inner and outer handles each co-operating with a hub to turn it and its lug, and means engaging one of said lugs to prevent movement thereof.

6. A lock including a case, a spring held latchbolt, a tumbler controlled lock bolt designed for key operation, a latchbolt operating lever pivotally mounted on said locking bolt and adapted for operation by the lock bolt operating key, lugs supported for turning movement in said case and designed to engage a portion of said lever to retract said latch-bolt, one of said lugs being effective to move said lock bolt, inner and outer handles each co-operating with a lug to turn it, and means for preventing operation of the latch and locking bolts from one side of said case.

7. A lock including a case, a spring held

latchbolt, a tumbler controlled lock bolt designed for key operation, a latchbolt operating lever pivotally mounted on said locking bolt and adapted for operation by the lock bolt operating key, lugs supported for turning movement in said case and designed to engage a portion of said lever to retract said latch-bolt, one of said lugs being effective to move said lock bolt, inner and outer handles each coöoperating with a lug to turn it, and means for preventing operation of the latch

5 and locking bolts from one side of said case, comprising an auxiliary bolt having a guard to close the key hole when the auxiliary bolt is protracted to prevent access to 15 said bolt, and a button operated stud engaging the lug operable by said outer handle to prevent turning.

In testimony whereof I have signed this specification.

CARL HOFFMAN.
